Edwin A. Hayes

UNITED STATES PATENT OFFICE.

EDWIN A. HAYES, OF NEW YORK, N. Y.

COVERING FOR STEAM-BOILERS.

SPECIFICATION forming part of Letters Patent No. 280,470, dated July 3, 1883.

Application filed September 13, 1882. (No model.)

To all whom it may concern:

Be it known that I, EDWIN A. HAYES, of the city of New York, and county and State of New York, have invented a new and useful Improvement 5 in Coverings for Steam-Boilers, Tanks, Pipes, &c.; and I do hereby declare the following to be a full, clear, and exact description thereof, which will enable those skilled in the art to make and use the same, reference being 10 had to the accompanying drawings, forming part of this specification, in which—

Figure 1 represents a plan view of one of the sections of which my covering is composed; Fig. 2, a longitudinal vertical section of the 15 same on the line $x-x$, Fig. 1; Fig. 3, a transverse section on the line $y-y$, Fig. 1; Fig. 4, a modified sectional view of my connecting device; Fig. 5, a view of two sections connected. Figs. 6 and 7 are views of boilers with my improved covering applied thereto.

Similar letters of reference indicate corresponding parts.

The object of my invention is to provide a suitable covering, that may be easily applied 25 and is readily removed, for boilers, steam-pipes, or other conductors or vessels, for the purpose of protecting them from the action of any exterior cold or heat that may tend to vary the temperature of the material contained within 30 the same.

My invention relates, primarily, to the protection of pipes and boilers containing steam against cold, which, causing a condensation of steam, impairs their usefulness, and also to the 35 construction of a sheet-metal cover that will be a perfect non-conductor, fire and water proof, and that may be readily removed and replaced without injury when the boiler is to be inspected or repaired, or that may be used again 40 in other places; and to that end it consists in the use of a sectional covering, the various sections composing the same being constructed of thin metallic sheets, covered with cork or equivalent material, treated so as to be water and fire proof, the extensions of the metallic sheets 45 being provided with suitable devices for connecting the same together, and in other minor details, hereinafter described.

Referring to the drawings, A represents a 50 sheet of sheet brass, tin, galvanized iron, or other suitable material, cut in length readily

handled, the edges of which are bent up at a right angle, thus forming a vertical curb or rim. The right-hand and front vertical extensions, A', being, however, bent in hook shape, so as to fit over and firmly clasp the left-hand and back vertical extensions, A'', of the adjoining section when two are put together, thus making a perfectly-strong connecting device without the use of the great number of bolts heretofore necessarily used for a similar purpose. In order to make a tighter and stronger joint, I usually 55 bend in hook shape the right-hand extensions of half the sections and the left-hand extensions of the remainder, so that when the covering is 60 put together a hook-extension will come between two plain edges, and vice versa, as will be seen by Fig. 5, while the construction of the front and rear edges, or of the longer sides, is never varied.

It will be seen that the connecting device consists, essentially, of a tongue and groove, A' forming the groove, and A'' the tongue. To facilitate the laying of my covering, I sometimes place the tongue and groove on the ends 70 of the sheet in a horizontal instead of a vertical position, as is seen in Figs. 4 and 7, where the groove A' and tongue A'' on the ends of the sheet A are horizontal, the side extensions, A' and A'', remaining always vertical.

B represents a secondary sheet or covering, of cork, cut in sheets to fit the sheet A and laid upon the top of the sheet A; and B' is a sheet of similar material, placed adjacent to the inner sides of the vertical extensions A'', as is 75 clearly shown in the drawings. The covering B may consist of thin sheets of cork, saturated with a solution of soda or other fire-proof mixture; or it may consist of granulated cork and any adhesive preparation adapted to be rolled 80 in sheet, or of any equivalent substance or compound that is fire and water proof, buoyant, and of light weight. The advantage of using the covering B is that it can readily be cleaned at intervals, and the ashes, dust, &c., that necessarily gather upon such coverings may be 85 washed off, the difficulty of doing which has proved an objection to other boiler-coverings; and in case the covering becomes wet the saltwater will not damage the same, whereas the 90 coverings heretofore used have been injured and sometimes rendered almost worthless from 95

this cause. The sections A B may be of any desired shape and dimensions, so that they may be readily handled, and are preferably arranged to break joints when in place on the 5 boiler or tank, as is shown in Figs. 6 and 7.

The U-shaped spacing-strips C and the flat holding-strips D are made of metal, and lie opposite each other upon the inner and exterior surfaces of the covering A B. The holding-strip D serves to hold the non-conducting cork sheet B in its place, and the spacing-strip C is for the purpose of keeping the metallic sheet A from lying directly upon the surface of the steam generator or conductor, and the two 10 strips are held together by a metallic screw-bolt, E, which goes through the holding-strip D, cork covering B, metal plate A, and spacing-strip C, as shown in Figs. 2, 3, and 4, the various parts being held firmly together by the 15 nut E'. By unscrewing the nut E' and removing the bolt E the spacing-strip C may be readily removed, in case it becomes flattened down, (thus allowing the sheet A to come too close to the surface of the boiler,) and a new spacing- 20 strip substituted therefor.

The strip F in Fig. 5, of wood, metal, or other suitable material, is placed against the outside of the vertical extensions A' when the various sections are joined, and it is held rigidly 25 thereto by the screw-bolts G, which go through the vertical extensions A' A² and the intermediate cork, B', and when the nuts G' are tightened the joints between the sections become air-tight, and no hot air can therefore escape. 30 The utility of my boiler-covering is increased by the dead-air space surrounding the boiler or steam-pipe, which serves to keep the heat in the boiler, and which may be utilized in cooling the boiler by opening the same to the atmosphere. The strip of felt H is placed in the 35 air-space under the joints of the various sections A B, as is shown in Fig. 6.

The construction of the minor parts of my covering may be varied, provided there is no essential departure from the general arrangement of parts shown and described. 45

The boiler-covering, formed as described, is of economical construction, is easily handled, may be readily taken apart when the boiler is to be inspected, or whenever it becomes necessary to obtain access to the boilers, and may then be placed in position again, or else may be applied, if desired, to any other boiler. It adds no appreciable weight to the tank or generator covered, is thoroughly fire and water 50 proof, is easily cleansed, and is a perfect non-conductor. 55

Having thus described my invention, what I claim, and desire to secure by Letters Patent in the United States, is— 60

1. In a boiler-covering composed of sections, the combination, with the metallic sheets A, with extensions forming connecting devices, of the secondary cork sheet B, substantially as and for the purpose described. 65

2. The combination, with the sheets A and covering B, of the holding-strips D, as set forth.

3. The combination, with the sheets A, covering B, holding-strips D, and spacing-strips C, of the bolts E and nut E', as and for the 70 purpose set forth.

4. The combination, with the sheets A and covering B, of the strip F and bolts G, substantially as and for the purpose described.

5. The combination, with the sheets A, covering B, and spacing-strips C, of the strip of felt H, substantially as described. 75

EDWIN A. HAYES.
